UNITED STATES PATENT OFFICE

CLARENCE WINFRED SPICER, OF PLAINFIELD, NEW JERSEY

HEAT-TREATING FURNACE

Application filed April 21, 1928. Serial No. 271,775.

My invention relates to heat treating furnaces of the rotary type particularly to that type of furnace which may be used for heat treating tubes, bars, or shapes of considerable length, and has for its object to provide an improved means whereby tubes or bars may be more uniformly heat treated than by the means heretofore employed, and to straighten the bars while being heat treated so that the product is in more perfect state than has been accomplished heretofore and at the same time obtain these objects in a shorter time and at less cost.

The foregoing and other features of my invention will now be described in connection with the accompanying drawings forming part of this specification in which similar characters of reference indicate like parts after which I shall point out in the claims those features which I believe to be new and desire to secure by Letters Patent:

In the drawings:—

Figure 1 is a side elevation of my rotary furnace with the feeder end at the right, close up against the heating chamber.

Figure 2 is an enlarged detail, in part section of one section of my heating chamber.

Figure 3 is an end elevation of the section shown in Figure 2.

Figure 4 is a top view of the feeding mechanism.

Figure 5 is an end view in part section of the feeding mechanism.

Figure 6 is a side view in part section of the feeding mechanism.

Figure 7 is an enlarged side view in part section of my quenching mechanism with a section of a tube passing through the core.

Figure 8 is a view on line 8—8 Figure 7.

In the carrying out of my invention I employ a specially constructed rotary heating chamber 10 which may be rotated on rolls 11 by a source of power which may be indicated as a sprocket 12. This chamber is made up of a plurality of units, in Figure 1. I show four of these units provided with flanged ends 13 by means of which the units may be bolted together to form a chamber of any desired length. At any convenient place on each unit

I provide a bearing guide 14 which is adapted to roll upon the rolls 11 of the cradles 15.

In the construction shown in Figure 2 I provide a cast iron shell 20 and co-axial therewith I use a tube 21 which may be made of any material of high heat withstanding properties and non-electrical conductivity, such as fused alumina. In between the tube 21 and the outer shell 20 I provide a packing of heat insulation material 22. The tube 21 is wrapped with a metallic ribbon 25 which serves as an electrical heat source the ends of which terminate in feeder rings 26 on the outside of the shell 20 but insulated therefrom. Brushes 27 are provided to ride on the feeder rings and these brushes are furnished with current supplied from outside source 28.

In Figure 2 I illustrate the source of current as an adjustable transformer. With this source it will be readily understood that the current supply and voltage may be regulated in each section to give the required amount of heat within the chamber. I do not wish to limit myself to this, however, as each section can be connected to standard voltage line, say 440 volts and by varying the connections of the four units from all in series to series parallel to all in parallel the required range may be effected.

It will be readily understood that I do not limit myself to electric heating of my furnace as any of the well known systems of furnace heating may be utilized.

On the feeding end I provide a feeding mechanism that revolves the tubes or bars at the same time that it feeds them longitudinally through the furnace. This device is mounted on a frame 40 and is provided with elevating means 41 to raise and lower the axis to adjust the lower surface of the tube or piece to be fed into the heating chamber in line with the lower surface of the chamber. Mounted to turn in bearings 42 I provide a carrier 43. This carrier is provided with bearings 44 and 45 in which shafts 46 and 47 are adapted to turn. These shafts carry rolls 48 and 49, having contours adapted to the shape of the bar or tube to be heat treated, and these rolls may be changed by slipping them off the shafts 46 and 47

and rolls with different contours substituted. It will be noticed that bearings 45 may be adapted to float in which case they may be backed by springs 50. This provides for frictional contact with the tube in spite of commercial variations in tube or piece sizes. On the ends of shafts 46 and 47 intermeshing gears 52-53 are provided, on the opposite end of shaft 46 I provide a gear 54. This gear meshes with gear 55 which is in turn secured to bevel gear 56 which unit is free to turn on pin or stud 57 secured in carrier 43.

The gear 56 is a planetary gear and runs on the circular rack 58 which is bolted or otherwise secured to the frame 40. On the carrier 43 I provide a sprocket 60, which is connected to a source of power and when revolving the planetary gear 56 travels around the circular rack 58 and thereby gives rotary motion to the feed rolls 48 and 49 through the train of gears just described in detail.

In Figure 1 I illustrate a feeding mechanism on both ends of my heat treating device. I may or may not use the feeding device on the left as I choose because it is readily apparent that it is not always necessary as one piece of material will be forced through the furnace by the feed of the subsequent pieces.

With a means to adjust the height of the feeding means and means to change the feed rolls it will be apparent that a variation of sizes and shapes of pieces may be taken care of, and no matter what the variation may be the piece will always lay straight at the proper longitudinal line at or near the bottom of the heating chamber and be uniformly subjected to heat and after it becomes free of the feeding rolls the tendency of the piece to roll on the circular interior of the heating chamber will in itself tend to straighten out the piece and make it more perfect than methods heretofore employed.

The feeding mechanism is held against the heating chamber and the space between the two is closed with a telescope spring extended member 70 to keep the amount of air entering the furnace at a minimum.

On the opposite end of the heating chamber from the feeding mechanism I provide, when required, a quenching device 80. This device is merely a means for supplying the cooling medium necessary to heat treating of the character described. For the purpose of this invention I employ a nozzle 81 which is connected to a water or other cooling medium supply at 82 and has a plurality of ports or holes 83 leading into an annular chamber 84. This chamber 84 has a central opening 85 a trifle larger than the tube or piece to be heat treated and a truncated conical orifice 86 the cross sectional area of

which is less than the combined area of the ports or holes 83.

It will be readily apparent that when water or other cooling liquid is under pressure the annular chamber will be completely full of water and that a conical column of water will spurt out of the slot 86 and be directed away from the furnace side of the quenching device. As the tube or piece 100 is forced into contact with the stream of water upon its entry in the hole 85 the cone of water follows the surface of the moving tube and quickly transfers the heat from the tube or piece to the water thereby cooling the tube and completing the proper quenching of the tube or bar.

I wish it distinctly understood that my heat treating furnace herein illustrated and described is in the form in which I desire to construct it and that any changes or modifications can be made as may be convenient or desirable without departing from the salient features of the invention and I therefore intend the following claims to cover such modifications as naturally fall within the lines of invention.

I claim:

1. In a rotary furnace, the combination of a heating chamber of substantially uniform diameter throughout, a quenching device, a feeding mechanism comprising means to longitudinally feed and rotate a comparatively long piece through the furnace, said means positively rotating the piece.

2. The device of claim 1 in which the heating chamber comprises a plurality of electrical resistance heated units, means to vary the heat in each unit.

3. The device of claim 1 in which the quenching device is provided with a central opening substantially co-axial with the furnace, means to inject a stream of cooling fluid into opening, to impinge upon the piece at an angle and at comparatively high velocity, means to permit the free escape of steam and cooling fluid away from the piece.

4. In a rotary furnace, the combination of a heating chamber comprising a plurality of units provided with central heating chambers, each unit independently heated, means to vary the heat in each unit, a feeding mechanism comprising means to longitudinally feed the substantially long piece to be heat treated into the furnace with a positive rotary motion, a conical stream of cooling medium, means to permit the free escape of steam and cooling medium away from the piece, means to feed the piece through the conical stream.

5. The device of claim 4 in which the feeding mechanism comprises a frame and rotating carrier, the rotating carrier provided with means to impart positive rotating and longitudinal motion to the piece to be heat treated.

6. In a rotating furnace, the combination of a heating chamber, a feeding mechanism comprising means to longitudinally feed and rotate a piece through the chamber said means positively rotating the piece at substantially the same speed as the furnace.

7. A rotary furnace provided with means for positively feeding a pipe through the furnace with combined longitudinal and rotary motion.

8. A method of simultaneously annealing and straightening a traveling tube comprising passing a tube through a furnace in contact with the wall thereof with a combined longitudinal and rotary motion and quenching while the tube is being longitudinally fed and rotated.

Dated this 20th day of April, 1928.
CLARENCE WINFRED SPICER.
